VARIABLE RESISTOR

Henry G. Richter, Westfield, N. J.

Application January 16, 1935, Serial No. 2,881

17 Claims. (Cl. 201—56)

This invention relates to variable resistors, and more particularly to moderately high resistance units of the wire-wound type.

The primary object of my invention is to generally improve wire-wound resistance elements. A more specific object of my invention is to provide a construction which will hold the resistance wire windings tightly in place even when dealing with fine wire wound at close pitch. Another object is to obtain good electrical contact between the resistance wire and appropriate soldering lugs without soldering and while using a minimum of simplified parts.

It is common practice, particularly with radio apparatus and the like, to associate a power switch with the resistor, said power switch being actuated during the first part of the movement of the control shaft of the resistor. It is desirable to actuate the power switch before rather than during resistance variation, which is best accomplished by elongating the short-circuited or terminal part of the resistance element, and the fulfilment of this desideratum constitutes another object of my invention.

It is sometimes sought to taper or step the rate of resistance variation, but this has been difficult to accomplish when dealing with wire-wound units. In accordance with a further object of my invention, I make it possible to step the resistance variation by simplified means, both this and the preceding object being accomplished while using standardized production parts similar to those used with a simple unit not having the features in question.

Still another object of my invention is to facilitate the production of tandem resistance units, that is, two or more independent units assembled into a single compact structure and controlled by a single control shaft. A further object of my invention is to so design the resistor that the casing of the unit may be interchangeably closed by a simple back or closure plate or a power switch or one or more tandem resistor units. Still another object of my invention is to make many of the parts of the resistor unit interchangeable with those used in a film type resistor shown in my application Serial No. 734,810 filed July 12, 1934, thereby making possible the ready assembly of tandem units having one resistance wound and one film type resistor, as well as simplifying the manufacturing problem by using a maximum number of parts common to both the film and wire-wound units.

To the accomplishment of the foregoing and such other objects as will hereinafter appear, my invention consists in the resistor elements and their relation one to the other, as are herein-after more particularly described in the specification and sought to be defined in the claims.

The specification is accompanied by a drawing in which:

Fig. 1 is a rear elevation of a resistor unit with the closure plate removed;

Fig. 2 is a section taken in the plane of the line 2—2 of Fig. 1 with the closure plate in place;

Fig. 3 is a section taken in the plane of the line 3—3 of Fig. 1;

Fig. 4 is a perspective view of an annular insulation plug forming a part of the resistor assembly;

Fig. 5 is a side elevation showing the manner in which units may be assembled in tandem;

Fig. 6 is a front elevation of the second or added unit shown in Fig. 5;

Fig. 7 is a side elevation showing the manner in which a power switch may be used for closing the resistor;

Fig. 8 is a front elevation of the power switch closure; and

Fig. 9 schematically illustrates an annular closure plug modified for a tapered or stepped wire-wound unit.

Referring to the drawing and more particularly to Figs. 1 through 4 thereof, the resistor comprises 25 a preferably cylindrical casing 12 having a side wall 14 and a front end wall 16, the opposite end of the casing being left open. As here illustrated, the casing is molded out of a single piece of insulation, but it may be formed of metal lined with insulation. The resistance is formed by an appropriate resistance wire 18 wound on a strip of insulation 20. It is convenient to make the strip 20 bendable, the resistance windings being applied thereto while the strip is straight, whereupon the strip is bent into arcuate configuration and inserted within the casing 12. An annular insulation plug 22 is then forced into the casing within the arcuately bent resistance element.

Soldering lugs 24, best shown in Figs. 1 and 3, are 30 preliminarily inserted in the casing, said lugs being L-shaped and having their inner ends 26 bearing against the outside of the terminal portions of the resistance winding. The plug 22 is 35 dimensioned for a force fit within the resistance element, and when pressed axially into position serves the dual function of locking the individual resistance windings tightly in place and of forcing the terminal parts of the windings tightly 40 against the soldering lugs, thereby insuring good 45 contact without the necessity of soldering or other special precautions. The leading or approach edge of plug 22 is preferably rounded or tapered slightly, as is indicated at 23 in Fig. 2.

The resistance is varied by a sliding contact 28 formed at the end of a preferably long resilient arm 30 secured to a radial arm 32 mounted on the control shaft 34. Arms 30 and 32 are here 50 illustrated as secured together by a tenon 36 on 55 60

arm 32 passing through arm 38 and riveted there-over. The inner end of arm 32 is pressed to form a dished hub 38 within which there is placed an insulation washer 40. The inner end of shaft 34 is squared at 42 and receives a metallic washer 44, an insulation washer 46, hub 38 with its insulation washer 40, and a stop arm 50, these parts all being riveted tightly on shaft 34, as is indicated at 52. The hole in hub 38 is, of course, 10 made larger than the squared end 42, so that the entire contact arm assembly is insulatedly mounted on the control shaft.

Electrical connection with the contact arm is made through soldering lug 54. The inner end 15 of this soldering lug forms a ring 56 which surrounds insulation washer 46 and bears in an axial direction against the face of hub 38. The ring 56 has struck thereon diametrically opposed teats 58 which ride on hub 38. The soldering 20 lug is formed of sheet metal sufficiently resilient to insure good electrical contact. It will be noted in Fig. 1 that soldering lug 54 enters casing 12 at the ends of the resistance element, thus avoiding contact with the resistance windings. 25 The lug is preferably recessed into the end wall 16 of the casing, as is best shown at 66 in Fig. 2, in order not to interfere with proper seating of the resistance element. The lug is held in place by insulation plug 22. The latter is preferably 30 recessed at 62 to insure proper registration of the parts, and this recess is occupied by a bend 64 in soldering lug 54.

Control shaft 34 is carried by a threaded metallic bushing 66 which is flanged at 68 and riveted to casing wall 16 at 70. The shaft is held against axial movement by thrust washer 44 at one end of the bushing, and a split thrust washer 72 sprung into a mating groove 74 on the control shaft at the other end of the bushing. 40 The resistor is completed by a preferably metallic closure plate 76 secured at the open end of the casing. Cylindrical casing wall 14 is preferably recessed at 78 to receive closure plate 76. The closure plate is circular except for a registration projection 80 which fits into a recess 82 on casing wall 14. While closure plate 76 is not shown in plan, the projection 80 is similar to that shown on the switch closure in Fig. 8. A ring of insulating material 82 may be interposed between the closure plate and the casing when assembling 45 the parts. The closure plate is held in place by a single assembly screw 84 which passes through the front wall 16 of the casing, then through a hole 86 in the plug 22, and finally is threaded 50 into the closure plate at 87. This assembly screw 84 is so located as not to interfere with the full desired range of movement of the contact arm 32.

Plate 76 has struck inwardly therefrom a stop lug 88 which cooperates with the afore-mentioned stop arm 50 to limit the movement of the control shaft.

If desired, the resistor may be combined with a power switch by substituting a switch closure for the simple closure plate heretofore described. 65 Such an arrangement is shown in Figs. 7 and 8. The resistor R corresponds to that heretofore described. The switch closure S comprises a plate 90 having the same outline as closure plate 76. This plate includes a registration lug 92 and 70 threaded hole 87, like those heretofore described, and a stop lug 92 which allows for the switch movement. The switch is mounted on plate 90, and electrical connection is made through soldering lugs 94. The switch is preferably of the 75 toggle type and is controlled by a rocker 96 to

which are secured bearing surfaces 98 which project through a window 100 in plate 90. Bearing fingers 98 lie in the path of movement of stop arm 50, and the parts are so arranged that when the stop arm reaches its end position, the switch is turned off, this being the condition of the parts shown in Fig. 8 in which the stop arm 50 is indicated by broken lines. It will be understood that when the resistor is turned from its end position, the switch is tripped during the first 10 part of the movement.

To avoid having the switch tripped only after traversing part of the resistance element, I short-circuit the resistance winding for an appreciable distance at the starting terminal. This is accomplished in a convenient manner at minimum cost by coating a part of the periphery of plug 22 with metallic paint, as is indicated at 102 in Fig. 4. I prefer to use a non-oxidizing metal like silver. When plug 22 is forced into place, the resistance 2 windings in contact with the silver coating 102 are short-circuited and rendered ineffective. The coating is dimensioned to compensate for tripping of the power switch. This feature may be used, of course, only with units intended to be equipped 2 with a power switch, but the expense is so slight that I find it more convenient to use the metallic coating 102 on all units, thereby standardizing the resistance value and adapting all units for the addition of a power switch.

This general idea of coating the periphery of the plug 22 may also be used to provide a so-called tapered resistance unit, that is, a unit in which the rate of change of the resistance is not uniform. Tapering is valuable and has been used with considerable success in film type resistance units but has been too costly for use in wire-wound units, as by varying the pitch of the winding or changing the size or material of the resistance wire. In accordance with my invention, the plug 22 may have a part of the periphery coated with a very low resistance film 104, as is indicated in Fig. 9. When such a plug is forced into contact with the wire windings, a part of the winding is changed to a compound wire and film type unit, thereby lowering the resistance value of part of the element while still retaining a current carrying capacity better than is attainable with a simple film type resistor. The short-circuiting terminal or metallic coating 102 may, of course, also be used.

A further feature of my invention concerns tandem units. Such units are troublesome to stock because of the variety of combinations required. I simplify this problem by adding one or more tandem units 110 to the standard resistor R, as is indicated in Fig. 5. Instead of closing the back of resistor R with a closure disc or power switch, the unit 110 is added which in turn is open at its back face and preferably made exactly like the back edge of the standard unit, so that the regular closure plate or power switch may in turn be used to close the casing of the tandem unit 110. The casing of unit 110 is molded like that of unit R except that the forward edge is stepped or shouldered at 112 and provided with a locating projection 114, so that the units will mate snugly together. The assembly screw 116 is approximately twice as long as before and passes through both units from end to end. Unit 110 in Figs. 5 and 6 is intended to generically represent a tandem unit of either film or wire-wound type. If wire wound, the internal mechanism of the unit is like that of unit R, the essential difference being that the

bushing and control shaft of unit 110 terminate at the unit, and the control shaft has riveted thereto a drive disc 118. This disc is slotted at 120, and the waste metal is bent outwardly to 5 form bearing surfaces 122 dimensioned to receive the stop arm 50 of unit R. Stop arm 50 then functions as a coupling rather than a stop arm, but the stop arm of unit 110 assumes the motion limiting function.

10 An important feature of the present invention resides in the fact that the external dimensions of casing 12, stop arm 50, disc 118, closure plate 76, and switch S are identical with the corresponding dimensions in the film type unit shown 15 in my copending application Serial No. 734,810 heretofore mentioned. This makes it possible not only to connect wire-wound units in tandem with one another and film type units in tandem with one another, but more important, to connect 20 wire-wound and film type units in tandem. Such flexibility of combination is valuable in meeting the varied requirements which arise in practice. In Figs. 5 and 6 the tandem unit 110 equally well represents a unit of the film type 25 or of the wire-wound type. If desired, the first unit (replacing R) may be of the film type and the second unit of the wire-wound type.

It is believed that the mode of constructing and using, as well as the many advantages of my 30 resistor, will be apparent from the foregoing detailed description thereof. The windings and soldering lugs are locked tightly in place and are held in good electrical contact by their assembly between an external ring and an internal plug. 35 This internal plug serves dual functions in receiving a metallic coating for short-circuiting terminal windings and in receiving a resistance or other conductive coating for tapering the resistance value. The assembly of tandem units is 40 facilitated and the combination of wire-wound and film type units made possible. Many of the parts of the wire-wound unit are identical with parts used in a film type unit, thereby simplifying manufacture. Sliding contact is made at the 45 side rather than the edge of the resistance element, thus presenting a larger surface for contact. The contact arm is long and readily yieldable, making for smooth even control.

It will be apparent that while I have shown 50 and described my invention in preferred forms, many changes and modifications may be made in the structures disclosed without departing from the spirit of the invention defined in the following claims.

55 I claim:

1. A variable resistor comprising a one-piece 60 casing having an end and a cylindrical side-wall, a bushing secured to said end, a control shaft passing through said bushing, an arcuately bent resilient contact arm mounted on said control shaft, an arcuate wire-wound resistance element placed inside the cylindrical wall of the casing, said resistance element being small in radial 65 dimension but broad in axial dimension, said cylindrical side wall having an axial breadth greater than that of the resistance element, an annular rigid insulation plug forced within said wire-wound element to hold the same tightly 70 against the cylindrical wall of the casing, said plug being substantially smaller in axial dimension than the element and bearing against the forward part of the inner wall of the element, said contact arm bearing against the remainder 75 of the inner wall of said element in back of said

plug, and a removable closure for closing the open back end of the casing.

2. A variable resistor comprising a cylindrical casing closed at one end, a bushing secured to 5 said end, a control shaft passing through said bushing, a contact arm mounted on said control shaft, an arcuate wire-wound resistance element placed inside the cylindrical wall of the casing, one or more soldering lugs having their inner 10 ends next to the windings, an annular insulation plug forced within said wire-wound strip, a stop arm mounted at the end of the control shaft, and a closure for the open end of the casing, said closure having a stop cooperating with said stop arm.

3. A variable resistor comprising a cylindrical casing closed at one end and open at the other end, a bushing secured to the closed end, a control shaft passing through said bushing, a contact arm and hub insulatedly mounted on the 20 inner end of said control shaft, an arcuate wire-wound resistance element placed inside the cylindrical wall of the casing, one or more soldering lugs having their inner ends next to the windings, an annular insulation plug forced 25 within said wire-wound strip, another soldering lug passing beneath said plug and bearing at its inner end against said hub, a stop arm mounted at the end of the control shaft, and a closure for the open end of the casing, said closure having a stop lug cooperating with said stop arm.

4. A variable resistor comprising a cylindrical casing closed at one end and open at the other end, a bushing secured to the closed end, a control shaft passing through said bushing, a contact arm and metallic hub insulatedly mounted on the inner end of said control shaft, an arcuate wire-wound resistance element placed inside the cylindrical wall of the casing, one or 35 more soldering lugs having their inner ends interposed between the windings and the casing, an annular insulation plug forced within said wire-wound strip in order to bind the windings and press the same into contact with the soldering 40 lugs, another soldering lug passing beneath said plug and having at its inner end a contact member bearing against the aforesaid hub, a stop arm mounted at the end of the control shaft, a closure for the open end of the casing, said 45 closure having a stop cooperating with said stop arm, and a single assembly screw passing through said casing, plug, and closure, said screw being so located as not to interfere with the desired 50 range of movement of the contact arm.

5. A variable resistor comprising a continuous 55 wire-wound resistance element, a contact movable thereover, and an insulation support external of the elements and forced against the outside of said element, said support being coated 60 with a conductive coating contacting with a part of said element.

6. A variable resistor comprising a cylindrical 65 casing wall, an arcuate wire-wound resistance strip carried within said wall, and a circular insulation plug forced within said arcuate resistance element, a part of the periphery of the plug being coated with a conductive coating.

7. A variable resistor comprising a cylindrical 70 casing wall, an arcuate resistance element carried within said wall, and a circular insulation plug forced within said arcuate resistance element, the periphery of the plug at one end of the element being coated with a metallic coating 75 in order to short-circuit a part of the element.

8. A variable resistor comprising a cylindrical casing wall, an arcuate wire-wound resistance strip carried within said wall, one or more soldering lugs having their inner ends next to the 5 resistance element, and an insulation plug forced within said arcuate resistance element, the periphery of the plug at one end of the wire-wound element being coated with a metallic coating in order to short-circuit a part of the 10 element, said plug acting to force the soldering lugs and the metallic coating into contact with the resistance element.

9. A variable resistor comprising a cylindrical casing wall, an arcuate wire-wound resistance strip carried within said wall, and a circular insulation plug forced within said arcuate resistance element, the periphery of the plug at one 15 end of the wire-wound element being coated for a substantial distance with a metallic coating in order to short-circuit a part of the element, a contact arm for varying the resistance, a power switch, and means associated with the contact arm for operating the power switch while the contact arm is at the short-circuited end of the 20 element.

10. A variable resistor comprising a cylindrical casing wall, an arcuate wire-wound resistance strip carried within said wall, one or more soldering lugs having their inner ends interposed between the resistance element and the cylindrical 25 wall, a circular insulation plug forced within said arcuate resistance element, the periphery of the plug at one end of the wire-wound element being coated with a metallic coating for a substantial distance in order to short-circuit a part 30 of the element, a contact arm for varying the resistance, a power switch, and means associated with the contact arm for operating the power switch while the contact arm is at the short-circuited end of the element.

11. A variable resistor comprising a cylindrical casing wall, an arcuate wire-wound resistance element carried within said wall, and a circular insulation plug forced within said arcuate resistance element, a portion of the periphery of 45 said plug being coated with a carbonaceous resistance film whereby a part of the element is given a different resistance value than the remainder of the element.

12. A variable resistor comprising a cylindrical casing wall, an arcuate wire-bound resistance element carried within said wall, one or more soldering lugs having their inner ends next to the resistance element, and a circular insulation plug forced within said arcuate resistance element, a portion 55 of the periphery of said plug being coated with a carbonaceous resistance film whereby a part of the element is given a different resistance value than the remainder of the element, said 60 plug acting to force the soldering lugs and the resistance film into contact with the resistance element.

13. A variable resistor comprising a cylindrical casing wall, an arcuate wire-wound resistance strip carried within said wall, one or more soldering lugs having their inner ends interposed between the resistance element and the cylindrical wall, and a circular insulation plug forced within said arcuate resistance element in order 65 to bind the wire windings in place and in order to force the windings and soldering lugs into good electrical contact, a portion of the periphery of said plug being coated with a low resistance film whereby a part of the resistance element is given 70

a different resistance value than the remainder of the element.

14. A variable resistor comprising a cylindrical casing closed at one end and open at the other end, a bushing secured to the closed end, a control shaft passing through said bushing, a contact arm mounted on said control shaft, an arcuate wire-wound resistance element placed inside the cylindrical wall of the casing, an annular insulation plug forced within said wire-wound strip, the periphery of said plug at one 10 end of the wire-wound element being coated with a metallic coating for a substantial distance, an arm mounted at the end of the control shaft, and a closure for the open end of the casing, said 15 closure including a power switch adapted to be operated by said arm, the parts being so proportioned that the switch is operated while the arm is at the metallic coated part of the plug.

15. A variable resistor comprising a cylindrical 20 casing closed at one end and open at the other end, a bushing secured to the closed end, a control shaft passing through said bushing, a contact arm mounted on the control shaft, an arcuate wire-wound resistance element placed inside 25 the cylindrical wall of the casing, one or more soldering lugs having their inner ends interposed between the windings and the casing, an annular insulation plug forced within said wire-wound strip, the periphery of said plug at one end of 30 the wire-wound element being coated for a substantial distance with a metallic coating, a stop arm mounted at the end of the control shaft, a closure for the open end of the casing, said closure including a power switch adapted to be operated by said stop arm, the parts being so proportioned 35 that the switch is operated while the arm is at the metallic coated part of the plug.

16. A non-uniform variable resistor comprising a uniform wire-wound resistance element including an insulation core and a uniform resistance wire wound thereon, an insulation support wall bearing against said element, a part of said wall being coated with a carbonaceous resistance film in order to give part of the wire-wound element 40 a different resistance value than the remainder of the element.

17. A variable resistor comprising a one-piece casing having an end and a cylindrical side wall, a bushing secured to said end, a control shaft 45 passing through said bushing, an arcuately bent resilient contact arm mounted on said control shaft, an arcuate wire-wound resistance element placed inside the cylindrical wall of the casing, said resistance element being small in radial dimension but broad in axial direction, said cylindrical side wall having an axial breadth greater than that of the resistance element, soldering lugs projecting outwardly from said casing and having their inner ends bent to lie between the 50 outside of the resistance element and the inside of the cylindrical wall of the casing, a rigid annular insulation plug forced within the wire-wound element to hold the same tightly against the soldering lugs and the cylindrical wall of the 55 casing, said plug being substantially smaller in axial dimension than the element and bearing against the forward part of the inner wall of the element, said contact arm bearing against the remainder of the inner wall of said element in 60 back of said plug, and a removable closure for closing the open back end of the casing.

HENRY G. RICHTER.
